(No Model.)

F. MINK.
WATCHCASE.

No. 511,055.

Patented Dec. 19, 1893.

THE NATIONAL LITHOGRAPHING COMPANY,
WASHINGTON, D. C.

UNITED STATES PATENT OFFICE.

FRITZ MINK, OF PHILADELPHIA, PENNSYLVANIA, ASSIGNOR TO THE KEYSTONE WATCH CASE COMPANY, OF PENNSYLVANIA.

WATCHCASE.

SPECIFICATION forming part of Letters Patent No. 511,055, dated December 19, 1893.

Original application filed December 19, 1889, Serial No. 334,344. Divided and this application filed April 15, 1890. Serial No. 347,989. (No model.)

To all whom it may concern:

Be it known that I, FRITZ MINK, of the city and county of Philadelphia, and State of Pennsylvania, have invented an Improvement 5 in Watchcases, of which the following is a specification.

My invention relates to watch cases, and consists of certain improvements, which are fully set forth in the following specification, 10 and shown in the accompanying drawings, which form a part thereof.

This application is a division of my application, Serial No. 334,344, filed December 19, 1889. In that application is shown a watch 15 case having a flange or support for the movement and an adjustable clamping ring secured to the case from the face side and pressing the movement down upon the flange or the support.

20 In the present invention the watch case center is formed with a flange or shoulder upon its upper side to support the movement and an annular screw threaded clamping ring is screwed from the back of the case to the center to force the movement down upon the shoulder and clamp it in place. The object 25 of this invention is to screw the watch movement securely and removably within the watch case by an adjustable device, which 30 may be adjusted to suit movements of different thicknesses. It is desirable for the perfect operation of a watch movement that it should be firmly secured within the case and that the dial plate should be firmly held or 35 secured to the front of the movement and not allowed to be loosened.

Different kinds and makes of movements are employed in watch making, and these vary more or less in thickness, and great difficulty 40 has been met with in adapting the same case to movements of different thicknesses without making alterations or changes therein. Difficulty has also been experienced in securely fastening the dial plate to the movement, which is a matter of great consequence 45 since the loosening of the dial plate interferes with the movement of the hands, and may entirely stop the watch or cause it to keep imperfect time. The object of this in- 50 vention is to overcome these difficulties and

to produce a watch case in which the movement clamping devices are adjustable so as to be suited without change or alteration in the case itself to movements of different thicknesses, and in which the dial plate is securely 55 held to the front of the movement and prevented from becoming loosened therefrom.

By employing an adjustable clamping ring, which is screwed down upon the movement, the latter is forced upon the annular supporting shoulder at the front of the center, or a uniform pressure about the entire frame of the movement so that it is secured evenly and firmly in place, while by unscrewing the clamping ring the movement may be readily 65 removed if desired. By screwing the clamping ring down to a greater or less degree it may be made to suit the particular thickness of the movement employed, and in that manner is adjustable to different thicknesses of 70 movement.

Referring to the drawings:—Figure 1 is a sectional side elevation of a watch case illustrating the principles of my invention. Fig. 2 is a plan view of the detailed clamping ring, 75 and Fig. 3 is a sectional side elevation of a portion of a watch case, illustrating a modification of my invention.

A is the watch case center, and provided upon its front which comes adjacent to the 80 bezel of a watch with a supporting flange or annular rim a.

B is the removable back.

C is the bezel carrying the glass D.

E is the movement having the usual flange 85 or rim e.

F is the clamping ring, provided with external screw threads f to engage with screw threads upon the center. The movement E is placed in the case after the back has been 90 removed, so that its rim e rests upon the flange or rim a of the center. The clamping ring F is then screwed to the center A down upon the rim e forcing it with a uniform pressure about its entire rim down upon the flange or 95 rim a of the center, so that the dial plate is clamped firmly in place. It will be seen that the ring F may be screwed down to a greater or less degree to suit the size of the movement E.

In the modification shown in Fig. 3 G is an inner glass carried by the clamping ring F at the back of the watch case under the cover B.

Having now described my invention, what 5 I claim as new, and desire to secure by Letters Patent, is--

1. A watch case having its center formed with a supporting flange at its front side adjacent to the face of the watch in combination 10 with the watch movement supported thereby and an adjustable clamping ring adapted to be screwed to the center from the back of the watch to clamp the movement against said flange.

15 2. A watch case having its center formed with a supporting flange at its front side adjacent to the face of the watch, in combination with the watch movement supported thereby and an adjustable clamping ring adapted to 20 be screwed to the center from the back of the watch to clamp the movement against said flange and a glass carried by said clamping ring.

3. A watch case consisting of a removable 25 back and bezel and a center having a supporting flange at its front side adjacent to the removable bezel and internal screw threads at its rear side adjacent to the removable back, in combination with a movement supported by said flange and an externally screw threaded adjustable clamping ring adapted to be screwed to the center down upon the movement to clamp it against the supporting flange of the center from the rear side of the 30 watch.

35 4. A watch case having its center formed with a supporting flange adjacent to the face side thereof, in combination with the movement supported thereby, and an adjustable 40 clamping ring adapted to be screwed to the

center from the back thereof to clamp the movement upon said supporting shoulder with capacity of adjustment to and from the supporting shoulder at the front of the watch case for movements of different thickness. 45

5. A watch case having its center formed with a supporting flange adjacent to the face side thereof, in combination with the movement supported thereby, an adjustable clamping ring adapted to be screwed to the center from the back thereof to clamp the movement upon said supporting shoulder with capacity of adjustment to and from the supporting shoulder at the front of the watch case for movements of different thickness and a back 55 or cover independent of said adjustable clamping ring.

6. A watch case formed with a supporting shoulder adjacent to the face side thereof and provided at its back with a screw threaded rim, in combination with a watch movement supported by said shoulder, and an adjustable clamping ring provided with screw threads for attachment to the screw threaded rim at the rear of the case, and having the 65 face upon which said screw threads are located unobstructed to permit adjustment of said clamping ring to or from the supporting shoulder at the front of the watch case, whereby said clamping ring is adapted to clamp the 70 movement upon said supporting shoulder and has capacity of adjustment for movements of different thickness.

In testimony of which invention I have hereunto set my hand.

FRITZ MINK.
